UNITED STATES PATENT OFFICE

LEONHARD KELLENBERGER, OF ST. GALLEN, SWITZERLAND

COMBINED SINGLE-STANDARD MILLING MACHINE AND COUNTER-ARM BRACES

Application filed November 12, 1930, Serial No. 495,135, and in Germany November 21, 1929.

This invention relates to the provision of counter-arm braces on single-standard milling machines in such a manner that each brace can continually remain connected with the respective machine. The counter-arm braces serve, as is known, for supporting the upper cross arm of the milling arbor and the table bracket so that there is obtained a rigid connection between these members and the base plate whereby the working pressure is transmitted to the foundation free from shakes, and the thus acting brace is arranged in such a manner that neither the working range within the machine, nor the space outside the same is obstructed in any way.

Single-standard milling machines have been designed for the working of bulky or unwieldy work pieces, the dimensions of which over all exceed the size of the working table. The efficiency of a milling machine is the greater, the more rigid the upper cross arm and the table support are connected with the base plate, that is to say, the less shakes are caused by the transmission of the working pressure. Provision has, therefore, been made, as is known, to connect the upper cross arm or cantilever with the table, or to support the table with respect to the base plate, by counter-arm braces. In most of these known cases these braces, termed sometimes also scissors, must be detached from the machine in order to render it possible to attach and detach bulky or unwieldy work pieces, milling arbors and supporting standards for such ones.

I am aware of the existence of counter-arm braces which are continually connected with the machine, these machines having pillar guides which can be collapsed downwardly telescopically so as to afford free access to the working table. Most of the thus designed machines are, however, unnecessarily high, and with others where it has been endeavored to reduce the height a part of the circular pillar guide projects beyond the table whereby, however, the working of bulky or unwieldy work pieces is rendered difficult. There exist also counter-arm braces that are continually connected with the respective machine in

this manner that they can be shifted vertically upwards, but these constructional forms suffer from the drawback that they extend too far upwardly into the space required for shaftings and belts, cranes, trolleys and travelling cabs, pulley blocks and the like.

All these and other drawbacks of the known constructions have been obviated in my present improved combined single-standard milling machine and counter-arm brace, in which the brace is so combined with the upper cross arm that it can be turned in a vertical plane, as well as shifted in a horizontal plane so that in its horizontal end position it is located at the side of said upper cross arm without diminishing the range of working and without entailing a greater height. The thus arranged counter-arm brace is, nevertheless, always ready for use at, or in connection with, the machine and can be shifted and turned easily and quickly into its vertical end position in which it can be clamped fast so firmly that a rigid connection between the members concerned is attained whereby the efficiency of the machine is considerably increased.

Further technical effects can be attained by the use of double counter-arm braces, of which selectively the one or the other or both can be used. When both braces are in their supporting position, the upper cross arm is centrally supported on both sides, but in many cases, especially where the working pressure is only slight, it is sufficient to employ only one of the braces, in which case the upper cross arm is centrally supported on only one side, but the milling arbor and the bearing support can be introduced into the machine without necessitating removal of that one brace. Finally, it is possible to employ the two members of the double counter-arm brace in crossed position, like scissors.

The invention is illustrated diagrammatically and by way of example on the accompanying drawings, on which Figure 1 is a side view of a one-standard milling machine having a counter-arm brace for connecting the upper cross arm with the vertically adjustable working table carrier; Figure 2 is a longitudinal view of the same machine; Figure 3 is a view similar to Fig. 1 and shows

a slightly modified constructional form in which the counter cross brace connects the upper cross arm with the base plate of the machine; Figure 4 is a plan of the machine shown in Fig. 3; Figure 5 is a side-view of a machine having a vertically adjustable top and a stationary working table; Figure 6 is a longitudinal view of the same machine, and Figure 7 is a longitudinal view of a one-standard milling machine with crossed counter-arm braces.

With all these constructional forms the standard or main standard *b* is fixed to the base plate *a* of the machine, and at the standard is guided either the vertically adjustable working table, as in Figs. 1, 2, 3, 4 and 7, or the vertically adjustable milling rest, as in Figs. 5 and 6. Upon the standard *b*, or at it, is supported the milling spindle *e* which carries the milling arbor *f* and rotates it. The arbor *f* is supported in known manner by the bearing holders *g* and *g*¹. The transverse top member *h* is supported at its overhanging end either relatively to the table carrier *c*, as in Figs. 1, 2 and 7, or relatively to the table base *c*¹, as in Figs. 5 and 6, or directly relatively to the base plate *a*, as in Figs. 3 and 4. The machine can, thus, be used with the top member or upper cross arm supported or not supported, just as required.

Concerning the further and chief details I refer first to Figs. 1 and 2, in which there are two counter-arm braces *i* and *i*¹ which are guided in the so-called shoe *k* that can be turned at the top member or upper cross arm *h* by means of a bolt *l* that is provided with a pinion *m* engaging a rack *n* provided at the brace *i* so that by turning said bolt by means of a crank *o* applied to it the brace *i* will be shifted in the guides of said shoe *k*. The brace *i* can be turned in the vertical plane and at the same time shifted horizontally (may be positively with the aid of a cam or cam disk), and it is in this way possible to bring it out of the range of working of the machine and to place it at the side of the top member or cross arm *h*, so that the brace cannot in any way interfere with the proper working of a bulky work piece, nor act as a hindrance outside the machine.

In Fig. 1 the counter arm brace *i*¹ is shown in an oblique position in which it has been lifted and shifted in the shoe *k* for about one half of its length, whereas the brace *i* is in vertical position.

The shoe *k* extends transversely with respect to the arm *h*, and the brace *i* is arranged at one end of said shoe and the brace *i*¹ at the other end of the same, as appears from Fig. 2. Each brace can be shifted in the shoe and can be turned by means of it with the aid of the members provided for this purpose and can assume a vertical, as well as a horizontal position; this latter position is indicated in

Fig. 1 in dotted lines. The two braces are located at the two sides of the arm *h*, outside the same, and are supported in their horizontal position not solely by the guide ways in the shoe *k*, but also by rolls *p*, as shown in Fig. 1. When the braces have been moved from this horizontal position into the vertical position (the oblique position of the brace *i* in Fig. 1 is one of the various possible intermediate positions), they are fixed in that position by means of grips or handles *r*¹ which are firmly connected with bolts extending forth from the table *c*, and there is a clamping plate *q*¹ provided which is pressed by the grip *r*¹ against the edge faces of said braces. The plate *q* has a slot *s* making the plate horizontally shiftable so that it can be shifted away first from the one brace and then, in opposite direction, from the other brace so that each thereof can be turned already when it is still in vertical position.

In the modification shown in Fig. 7 in which the two braces cross one another, each brace has at its lower end a vertical slot *t* through which the fastening bolt passes and outside of which a clamping nut is located upon that bolt. It is obvious that with this constructional form the two braces can be shifted independent from one another.

In Figs. 3 and 4 three clamping bolts and grips are provided, viz., an upper bolt with grip *r*, a lower bolt with grip *r*², and a middle bolt with grip *r*¹.

The upper bolt engages the arm *h*, the lower bolt engages the base plate *a*, and the middle bolt engages the table *c*. It is, thus possible, to connect all these members very rigidly with one another. *q*, *q*¹ and *q*² are the clamping plates pertaining to said bolts and grips and acting upon the braces in accurately the same manner as has been described with regard to Figs. 1 and 2.

In the further modification shown in Figs. 5 and 6, the invention is applied to a one-standard milling machine in which the working table is not vertically adjustable, but in which, instead thereof, the member *d* holding the milling arbor *f* is vertically adjustable along guides provided at the standard. The upper cross arm *h* is in this instance combined not with two braces, but only with one brace *i*, resembling an **H** (Fig. 6) and there is, thus, between the upper legs of the **H** a free space affording access to the arbor *f* so that the brace need not be removed from its vertical position for the insertion of the suspended arbor carriers *g* and *g*¹. The brace is also in this instance guided in the turntable shoe *k* and can be placed parallel to the arm *h* at the two lateral faces thereof, as indicated by dotted lines in Fig. 5. *q* and *r*, as well as *q*¹ and *r*¹, are accurately such fastening and clamping members as the members in Fig. 3 denoted with the same letters of reference.

In Fig. 7 which has already been referred to in a preceding part of this specification, matters are practically just the same as with the other constructional forms, in that each 5 of the two braces can be shoved upwardly in the appertaining shoe *k* and then turned in such a direction that it finally lies parallel to, and at the side of the arm *h*.

There are in this case two individual shoes 10 *k*, the one at the right and the other at the left of the free end of said arm. The clamping plate *q* is practically just such a one as the clamping plate *q*¹ of Fig. 2, in that there is in it a horizontal slot *s* permitting shifting 15 of the plate to the right and to the left. *l* denotes the pivots of the shoes *k*, *e* the arbor, and *r* is the clamping lever for the plate *q*, accurately as in Fig. 1.

I claim:

- 20 1. A combined single-standard milling machine and counter-arm brace, comprising, in combination with the upper cross arm of said machine, a turnable guide member at the free end of said arm, a brace shiftable in said 25 guide member and adapted to be turned together with it into a position in which it lies parallel to the said arm at a side thereof, and means for fastening the said brace in its operative vertical position.
- 30 2. A combined single-standard milling machine and counter-arm brace, comprising, in combination with the upper cross arm of said machine, turnable guide members at the free 35 end of said arm, braces shiftable in said guide members and adapted to be turned together with them independent from one another into a position in which each brace lies parallel to the said arm at a side thereof, and means for fastening the said braces in their operative 40 vertical position.
3. A combined single-standard milling machine and counter-arm brace, comprising, in combination with the upper cross arm of said machine, turnable guide members at the free 45 end of said arm, braces shiftable in said guide members and adapted to be turned together with them independent from one another into a position in which each brace lies parallel to the said arm at a side thereof, and means 50 for fastening the said braces in their operative vertical position, the arrangement being such that the braces cross one another in this position, substantially as set forth.

In testimony whereof I affix my signature.
55 LEONHARD KELLENBERGER.
